(57) **CLAIM**

The ornamental design for a charger as shown and described.

DESCRIPTION

FIG. 1 is a perspective view of a first embodiment of a charger from above and the left side;

FIG. 2 is a perspective view from below and the right side thereof;

FIG. 3 is a rear view thereof;

FIG. 4 is a right side plan view thereof;

FIG. 5 is a front view thereof;

FIG. 6 is a left side view thereof;

FIG. 7 is a plan view thereof;

FIG. 8 is a underneath plan view thereof;

FIG. 9 is a perspective view of a second embodiment of a charger from above and the left side;

FIG. 10 is a perspective view of the second embodiment of a charger from below and the right side thereof;

FIG. 11 is a front view thereof;

FIG. 12 is a rear view thereof;

FIG. 13 is a left side view thereof;

FIG. 14 is a right side view thereof;

FIG. 15 is a plan view thereof; and,

FIG. 16 is an underneath plan view thereof.

The dash-dash lines within the Figures show at least portions of the charger and form no part of the claimed design. The dash-dot lines within the Figures and the areas within the dash-dot lines show at least portions of the charger that form no part of the claimed design.

1 Claim, 16 Drawing Sheets
